[57] **CLAIM**

The ornamental design for a microwave pressure cooker, as shown and described.

DESCRIPTION

FIG. 1 is an exploded perspective view of the microwave pressure cooker showing our new design;

FIG. 2 is a bottom perspective view of the pot shown separately for ease of illustration;

FIG. 3 is a top plan view thereof;

FIG. 4 is an exploded right side elevation view, the left side elevation view being identical;

FIG. 5 is a front perspective view thereof; and,

FIG. 6 is an enlarged and exploded fragmentary perspective view of the latch area circled on FIG. 5.
